UNITED STATES PATENT OFFICE.

PETER COOPER HEWITT, OF RINGWOOD MANOR, NEW JERSEY, ASSIGNEE, BY MESNE ASSIGNMENTS, TO COOPER HEWITT ELECTRIC COMPANY, OF HOBOKEN, NEW JERSEY, A CORPORATION OF NEW JERSEY.

VAPOR ELECTRIC APPARATUS.

1,197,629.

Specification of Letters Patent. Patented Sept. 12, 1916.

Application filed September 19, 1912. Serial No. 721,317.

To all whom it may concern:

Be it known that I, PETER COOPER HEWITT, a citizen of the United States, and resident of Ringwood Manor, county of Passaic, State of New Jersey, have invented certain new and useful Improvements in Vapor Electric Apparatus, of which the following is a specification.

This invention relates to vapor electric apparatus of the well known Cooper Hewitt type comprising an exhausted container or envelop provided with positive and negative electrodes insulated from one another with respect to the container, the negative electrode being composed of material of such a nature that the particles thereof will reunite physically and electrically on contact with one another after separation under the conditions obtaining within the container.

Devices of the above character can be arranged to perform a number of different functions, such for instance, as rectifying an alternating current or the production of rays having various characteristics and wave lengths.

The present invention relates more particularly to apparatus designed for the production of ultra-violet rays which can be usefully employed for sterilizing and for promoting chemical and physical actions in liquid and solid substances.

The efficiency of a vapor electric apparatus as a source of ultra-violet rays is found to depend to a great extent on the material of which the negative electrode is composed when its vapor serves to carry the current, and according to the present invention I employ as a negative electrode certain metals, the vapors of which when utilized in an apparatus of the above character emit a large number of rays having a wave length of between 2,000 and 4,000 $\mu\mu$ or in other words .000002 and .000004 meters.

As an example of a metal having the above characteristics which I have found to be especially suitable for this purpose I may mention thallium, the spectrum of which when employed in a vapor electric apparatus, gives, out of the total rays emitted by the vapor, a large proportion of rays having well defined wave lengths within the above limits, and another metal which is also suitable for this purpose is caesium.

It will be understood that the substitution 55 of these metals for mercury, which is the metal commonly employed in vapor electric apparatus as hitherto constructed, will, generally speaking, necessitate an alteration in the conditions under which the apparatus 60 is operated owing to the different vapor tensions of the metals employed according to my invention, but the general nature of the operation of the apparatus is otherwise 65 the same as when mercury is employed as the metal of which the negative electrode is composed.

In the drawings herein is shown a device well suited to the production of abundant ultra violet rays by the use of the system 70 herein described.

1 is an exhausted container having a chamber, 3, at one end and a mercury electrode, 2, with a lead, 4, adjacent thereto and also having at the other end a recess containing an electrode, 5, of thallium or caesium and a starting band, 7, together with a lead, 6, for said electrode. The starting band, 7, is connected by a conductor, 8, with the lead 4. The electrode 2 will act 75 as an anode and the electrode 5 as a cathode. As the passage of current through the device vaporizes the thallium or caesium, this material gives off ultra violet rays under the influence of the current which rays 80 may be utilized for various purposes. In starting the device use may be made of the starting band, 7, as is well known in the art.

As the metals above mentioned are solid 90 at ordinary temperatures the apparatus may be either started into operation by impressing a momentary high potential thereon, or the apparatus may be first heated so as to render the metal of the negative 95 electrode liquid, after which the apparatus may be started in the same manner as a mercury vapor apparatus.

Having now particularly described and ascertained the nature of my said invention 100 and in what manner the same is to be performed, I declare that what I claim is:—

1. A source of ultra violet rays comprising an exhausted container, an anode and a cathode therein, the latter being constituted 105 of thallium, and means whereby current may be conveyed within the container including starting means.

2. A source of ultra-violet rays comprising an exhausted container, an anode and a cathode therein, and thallium gas or vapor only between the anode and the cathode.
5. 3. A source of ultra-violet rays comprising an exhausted container, an anode and a cathode therein, the latter being constituted of thallium.

Signed at New York in the county of New York and State of New York this 10 18th day of September A. D. 1912.

PETER COOPER HEWITT.
